UNITED STATES PATENT OFFICE.

HENRY W. PLEISTER, OF WESTFIELD, NEW JERSEY, ASSIGNEE TO HENRY B. NEWHALL;
HENRY B. NEWHALL, JR., EXECUTOR OF SAID HENRY B. NEWHALL, DECEASED.

GUY-CLAMP.

1,288,176.

Specification of Letters Patent.

Patented Dec. 17, 1918.

Application filed May 18, 1917. Serial No. 169,602.

To all whom it may concern:

Be it known that I, HENRY W. PLEISTER, a citizen of the United States, residing at Westfield, in the county of Union and State 5 of New Jersey, have invented certain new and useful Improvements in Guy-Clamps, of which the following is a specification, taken in connection with the accompanying drawings.

10 My invention relates to guy clamps, and more particularly to such guy clamps as are used in telephone and telegraph installations. The advantages of my invention will be more fully hereinafter pointed out in the 15 specification and claims.

In the accompanying drawings, in which the same reference numerals refer to similar parts in the several figures.

Figure 1 is a longitudinal vertical section through my improved guy clamp before coöperating with a messenger;

Fig. 2 is a longitudinal vertical section through my guy clamp showing it coöperating with a messenger and showing the curve 25 of the weakened portions, somewhat exaggerated for the purpose of clearer illustration;

Fig. 3 is a longitudinal vertical section substantially on the line 3—3 of Fig. 4 30 showing the guy clamp and the supplemental bridging members and bolts;

Fig. 4 is a plan view of my guy clamp complete with the supplemental bridging members in position;

35 Fig. 5 is a longitudinal vertical section substantially on the line 5—5 of Fig. 4;

Fig. 6 is a transverse vertical section on the line 6—6 of Fig. 4;

40 Fig. 7 is a transverse vertical section on the line 7—7 of Fig. 4 and Fig. 3;

Fig. 8 is a side elevation of the threaded bridging member.

Fig. 9 is a side elevation of the unthreaded bridging member.

45 The common practice of running messenger strands between poles, up to a comparatively recent date, was to take the end which would not reach to the next pole, known among the linemen as the "dead end," and 50 wrap it around the last pole reached. This caused a loss of from approximately ten to one hundred feet of most expensive wire messenger strand.

In the new practice the messenger strand 55 is continued without wrapping or other in-

terruption by means of connections should the end of messenger strand not extend to the next pole. The free end of the messenger strand is bent back on itself forming an eye (not shown) which engages the end 60 of the next stretch of messenger.

The end of the messenger which is bent back is secured by means of several guy clamps to obtain the necessary holding capacity. The slipping of the guy clamps is 65 very dangerous for the reason that it may occur when a lineman is in a boatswain's seat between poles causing loss of life. Or if the guy clamp is used to brace a pole the guy clamp might slip when the pole is un- 70 der heavy wind or sleet pressure permitting the pole and wires to fall. For these reasons a plurality of ordinary guy clamps have to be used for each connection which necessitates an additional outlay and additional labor in installing them. Ordinarily 75 a plurality of standard guy clamps are used on each interlocking end of the strand.

Where the exact ultimate strain, that will be placed upon the guy clamp is known, at 80 the time of its original installation, a clamp of the requisite holding capacity will be permanently used. In actual practice, however, it is difficult and often impossible to forecast for a period of months or years 85 the exact ultimate strain that will be thrown upon any part of the installation including the guy clamps. When additional wires or cables are mounted upon a previously equipped installation new and additional 90 strains are thrown upon that installation. These have to be compensated for immediately for there is danger of an accident due to a storm or other strains. In cases where a greater load is developed, after the 95 initial installation, additional guy clamps have to be mounted provided there is a sufficient length of the dead end of the messenger left in reserve. In cases where there is not a sufficient length of the messenger to 100 permit the installation of additional guy clamps, it is necessary to take the work down entirely and replace it with a heavier construction. All this requires a great amount of labor and expense. 105

By my invention I avoid this labor and expense. By using that portion of my guy clamp minus the supplemental bridging members and bolts, the clamp will perform its ordinary function of taking the original 110

initial strain upon the messenger. After a period of months or years should any additional strains and stresses be thrown upon the messenger due to additional wires or cables, or for any other reasons, the additional load can be taken care of by the original guy clamp, originally installed, simply by adding thereto supplemental clamping members. These clamping members 10 approximately double the holding capacity of the clamp. Furthermore, they require no additional length of dead end of the messenger to install them.

The whole additional load can be instantly compensated for, at the minimum expense of material and labor, by simply adding the supplemental clamping members to my guy clamp as originally installed. Of course, where it is desirable for any reason to initially install a powerful guy clamp, of approximately double the holding capacity of an ordinary guy clamp, my guy clamp may be mounted, with its supplemental clamping members, on the original installation of the system, such an instance, for example, may occur in practice where the dead end of the messenger is short and will not permit of more than one guy clamp.

In the form of my invention shown in the drawings, my guy clamp 1 consists of the clamping member 2 having the unthreaded bosses 3, 3 and the weakened portions 4, 4. The clamping member 5 is provided with the screw threaded bosses 6, 6 and also with weakened portions 7, 7. These weakened portions may be formed in different ways. I preferably form them concave. In the weakened portion 4, 4 of the member 2, I arrange the openings 8, 8 and in the weakened portion 7, 7 of the clamping member 5, complementary aligned openings 9, 9. These openings 8 and 9 serve to further weaken the weakened portions 4 and 7, respectively, save metal, and also permit the passage of the supplemental clamping bolts to be herein-after referred to. The bosses 6, 6 are provided with interior screw threads 10, to coöperate with the bolts 11, 11.

When my guy clamp is used with the messenger 12 upon the original installation,—that is, assuming that the supplemental clamping members are not used on the original installation, though of course in many instances they may be,—the messenger 55 is clamped in the grooves 13, 13 of the clamping members 2 and 5. The bolts 11, 11 under service conditions each develop approximately sixteen thousand pounds tensile strain, which of course requires the use 60 of a very heavy wrench to coöperate with the heads 14, 14.

The messenger strand 12 will be powerfully gripped by that portion of the clamping members 2 and 5, adjacent to the respective bolts 11, 11. There will not be

such a powerful tensile strain upon the messenger 12 at points lying between the bolts 11, 11. The weakened portions 4 and 7 permit the metal of the clamping members 2 and 5 to yield or spring slightly between 70 the bolts 11, 11. In the drawings, particularly in Fig. 2, the yielding of the metal at the weakened portions is exaggerated for the purpose of clearer illustration.

Under ordinary service conditions my guy 75 clamp may be used as illustrated in Fig. 2.

In those cases, however, where additional strains are thrown upon the system after the original installation, these additional strains

can be instantly compensated for by adding 80 to my guy clamp, previously installed, supplemental clamping members. These supplemental clamping members may, of course, be variously formed. For purposes of illustration, I have shown these supplemental 85 clamping members as bridging members 15, 16 and a bolt 17. The bridging member 16 is provided with an opening 18 for the free 90 passage of the bolt 17, while the bridging member 15 is provided with interior screw 95 threads 19 to coöperate with the screw threads of the bolt 17. By mounting two sets of these bridging members in the openings 8 and 9, the metal of the clamping members 2 and 5 at the weakened portions 4 and 95 7, will be bent back and made to grip the messenger strand 12 with the same force as it is gripped immediately adjacent to the bolts 11, 11. Due to the yielding of the metal, by the use of this weakened portion, 100 this additional clamping of the messenger will not weaken or relax the compression of the bolts 11, 11 already installed.

I have found in practice that the best results are obtained by providing the bridging members 15 and 16 with substantially 105 concave surfaces 20, 21 so as to throw their bearing surfaces 22, 22 in substantial alignment with the axis of the messenger strand 12. While this is the preferred construction 110 it is of course to be understood that any other form of supplemental clamping member can be used.

When my guy clamp is originally installed 115 the heads of the bolts 14, 14 lie on one side of the clamp with an adequate space between them for the manipulation of the powerful wrench which is required in practice. When the supplemental clamping members are positioned, I place the heads 120 23, 23 on the opposite side of the guy clamp so that they can be readily manipulated by the same large wrench. The clamping members 16, 16 are preferably of sufficient thickness or height to insure that the heads 23, 23 125 of the supplemental bolts will lie in a different horizontal plane from the ends 24, 24 of the bolts 11, 11 so as to permit the ready manipulation of the heads 23, 23 by the large wrench necessary in this work. 130

The supplemental clamping members 15 and 16 together with their bolt 17, may be sold as separate articles of manufacture, or my guy clamp may be sold equipped with 5 the supplemental clamping members. These members as well as the clamping members 2 and 3 of my guy clamp, are preferably made of malleable iron.

By the use of my guy clamp the engineers 10 installing the system need not specify guy clamps of the greatest holding capacity, greatly in excess of the then requirements. They can use a cheaper and lighter guy 15 clamp, amply sufficient for their present needs, knowing that later, if the load is greatly increased, the additional strains on the guy clamps can be instantly taken care of by the comparatively inexpensive supplemental clamping members, which can be 20 used at the minimum expense of time and labor. This will reduce the cost of original installation.

Having thus described this invention in connection with illustrative embodiments 25 thereof, to the details of which I do not desire to be limited, what is claimed as new and what I desire to secure by Letters Patent is set forth in the appended claims.

What I claim as my invention and desire 30 to secure by Letters Patent is:—

1. A guy clamp formed of a plurality of clamping members, means to clamp said members together, and one or more registering openings in said clamping members in- 35 termediate said clamping means.

2. A guy clamp formed of a plurality of clamping members, means to clamp said members together, one or more registering openings in said clamping members, and 40 supplemental clamping means adapted to coöperate with said registering openings.

3. A guy clamp formed of a plurality of clamping members, means to clamp said members together, one or more registering 45 openings in said clamping members, and supplemental members and bolts adapted to coöperate with said registering openings.

4. The combination in a guy clamp of a clamping member having a plurality of 50 openings for the free passage of bolts, a clamping member having screwthreaded bosses, bolts to coöperate with said openings and screwthreaded bosses, said clamping members being provided with additional 55 registering openings.

5. The combination in a guy clamp of a clamping member having a plurality of 60 openings for the free passage of bolts, a clamping member having screwthreaded bosses, bolts to coöperate with said openings and screwthreaded bosses, said clamping members being provided with additional 65 registering openings and supplemental clamping means coöperating with said additional registering openings.

6. The combination in a guy clamp of a clamping member having a plurality of openings for the free passage of bolts, a clamping member having screwthreaded bosses, bolts to coöperate with said openings 70 and screwthreaded bosses, said clamping members being provided with additional registering openings and supplemental members and bolts coöperating with said additional registering openings. 75

7. The combination in a guy clamp of a clamping member having a plurality of openings for the free passage of bolts, a clamping member having screwthreaded bosses, bolts to coöperate with said openings 80 and screwthreaded bosses, said clamping members being provided with additional registering openings, and supplemental bridging members and bolts coöperating with said additional registering openings. 85

8. The combination in a guy clamp of two clamping members provided with grooves to receive a messenger and also provided with means to clamp said clamping members to said messenger, of weakening portions between said clamping means including aligned openings through said clamping members. 90

9. The combination in a guy clamp of two clamping members provided with grooves to receive a messenger and also provided 95 with means to clamp said clamping members to said messenger, of weakening portions between said clamping means including aligned openings through said clamping members, supplemental bridging members adapted to 100 bear directly above the grooves in the clamping members to exert the full power of the supplemental bolts directly in line of the axis of the grooves which contain the messenger strand and supplemental bolts coöperating with the bridging members. 105

10. In a guy clamp the combination of two clamping members, having weakening portions, means to clamp the clamping members together, and supplemental clamping means 110 to clamp the weaken portions of the clamping members.

11. In a guy clamp the combination of two clamping members having weaken portions provided with aligned openings, means 115 to clamp the clamping members together and supplemental bridging members and bolts to clamp the weaken portions of the clamping members.

12. A guy clamp composed of two major 120 clamping members, and provided with auxiliary reinforcing clamping members to increase the compression of the sides.

13. In a guy clamp the combination of a plurality of clamping members of the required length to give the requisite holding capacity for normal strains, means to clamp 125 said members together to obtain the requisite holding capacity for normal strains, and additional clamping means operating on same 130

clamping members to give the requisite holding capacity for abnormal strains.

14. In a guy clamp the combination of a plurality of clamping members of the required length to give the requisite holding capacity for normal strains, bolts to clamp said members together to obtain the requisite holding capacity for normal strains, and additional bolts operating on the same clamping members to give the requisite holding

capacity for abnormal strains, the heads of the additional bolts being located on the opposite side of the guy clamp from the heads of the other bolts to permit engagement by a suitable tool.

HENRY W. PLEISTER.
